(57) **CLAIM**

The ornamental design for the electric liquid vaporizer, as shown.

DESCRIPTION

FIG. 1 is a perspective view of an electric liquid vaporizer showing our new design;

FIG. 2 is a front view of the electric liquid vaporizer of FIG. 1;

FIG. 3 is a rear view of the electric liquid vaporizer of FIG. 1;

FIG. 4 is a right side elevational view of the electric liquid vaporizer of FIG. 1;

FIG. 5 is a left side elevational view of the electric liquid vaporizer of FIG. 1;

FIG. 6 is a top plan view of the electric liquid vaporizer of FIG. 1;

FIG. 7 is a bottom plan view of the electric liquid vaporizer of FIG. 1;

FIG. 8 is an exploded view of the electric liquid vaporizer of FIG. 1 showing the separated housing unit (top) and bottle portion (bottom);

FIG. 9 is a front view of the housing unit of the electric liquid vaporizer of FIG. 1, shown separately for clarity of illustration;

FIG. 10 is a rear view of housing unit of FIG. 9;

FIG. 11 is a right side view of the housing unit of FIG. 9;

FIG. 12 is a left side view of the housing unit of FIG. 9;

FIG. 13 is a top view of the housing unit of FIG. 9; and,

FIG. 14 is a bottom view of the housing unit of FIG. 9. The broken line showing of environmental structure in FIGS. 1 and 3-14 is for illustrative purposes only and forms no part of the claimed design.
